UNITED STATES PATENT OFFICE.

LOUIS E. BINSFELD, OF DETROIT, MICHIGAN, ASSIGNOR OF ONE-HALF TO JOSEPH J. TREPPA, OF DETROIT, MICHIGAN.

REVERSIBLE TABLE.

1,077,901.

Specification of Letters Patent.

Patented Nov. 4, 1913.

Application filed March 8, 1913. Serial No. 753,102.

To all whom it may concern:

Be it known that I, LOUIS E. BINSFELD, a citizen of the United States, residing at Detroit, in the county of Wayne and State 5 of Michigan, have invented certain new and useful Improvements in Reversible Tables, of which the following is a specification.

This invention relates to table tops, and comprises especially means for reversing the 10 table top sections or leaves for the purpose of exposing either side thereof. One side of the leaves or sections may be highly polished for special use and the other side may be rough for use as a kitchen table or other 15 inferior purposes. The table top is capable of extension, but the extensible features are not particularly pertinent to the reversible features to which the invention is particularly directed.

20 The invention is particularly applicable to the leaves or top sections of a round table, and is so illustrated. Each leaf or section is mounted on a pivot so that it will turn on a vertical axis, and the pivot is connected 25 to the leaf by a hinge, so that it will also swing on a horizontal axis, and in reversing each leaf it is first swung on the hinge to an upright position and then turned around on the pivot at the center to permit it to 30 be swung down again on the top frame with the opposite side uppermost. Means are provided for raising the leaf above the surface of the table, so that while it is being turned on its pivot it will not contact with 35 or scratch the surface of the opposite leaf.

The invention is illustrated in the accompanying drawings in which—

Figure 1 is a top view of the table. Fig. 2 is a similar view with one of the leaves in 40 the act or position of being turned. Fig. 3 is a cross section showing the inner edge of one of the top sections. Fig. 4 is a similar view with the leaf elevated in position to be 45 swung around. Fig. 5 is a plan of a latch mechanism for holding the leaves in adjusted position.

Referring specifically to the drawings, 6 indicates the ordinary extension slides of a table, which will be supported on the legs in 50 any suitable way, and upon these slides are mounted respectively base frames or sills 7 and an edge frame 8, which latter forms a boxing under the table leaf. These leaves or sections are indicated at 9, and the operation of each is identical. Each leaf 9 is

hinged at the middle of its inner edge, as indicated at 10 (the hinge being sunken in the edge) to a pivot pin 11 which is movable up and down in a sleeve 12 located at the center of rotation and fixed to the adjacent 60 sill 7. An arm 13 is pivoted at one end to the sleeve, conveniently by extending the sleeve through a hole in the arm, and the outer end of the arm is turned up and pivoted at 14 to the edge of the leaf, at the 65 corner where the circumferential and diametrical edges meet, the pivot 14 being substantially concentric with the pintle of the hinge 10. By reason of this construction, the leaf 9 may be swung up vertically and 70 reversed to place either side uppermost. The pivot 11 also permits the leaf to be swung around on a vertical axis formed by the pivot, and illustrated in Fig. 2, and in order to guide this movement the semi-circular casting or side piece 8 is provided on the inside with a grooved track 15 extending around the same, and this is engaged by the head 16 at the end of a bracket 17 fastened to the underside of the arm 13. 75

Before turning the leaf on the vertical axis it is desirable that one side thereof be lifted so that it will clear the top surface of the opposite leaf, as shown in Figs. 2 and 4, when it is being swung around, and to 80 accomplish this I provide a wedge 17 which slides in a guide 18 secured to the side of the sill 7 and which works through a slot in the tube 12, and under the lower end of the pivot pin 11, as shown in Figs. 3 and 4. 85 This wedge may be slid either way by means of a lever 19 which is fulcrumed on the sill 7 and connected to the wedge by a link 20 and projection 21. When the wedge is pushed to the left, as in Fig. 3, to permit 90 the pin to drop, the lever 19 folds or lies within or under the edge of the leaf. When the wedge is pulled to the right, as shown in Fig. 4, its inclined edge, acting under the pin 11, lifts said pin, and thereby raises the 100 leaf so that when swung around it will clear the top of the other leaf.

To latch or hold each leaf in position I provide the latch devices shown particularly in Fig. 5, which mechanism is located or 105 housed within the leaf, which will ordinarily be made of two boards spaced apart, and indicated at 22 in Fig. 3, with suitable edge or spacing pieces 23, the mechanism shown in Fig. 5 being housed between the boards 110

22. One of these boards may be of fine wood highly polished, and the other of inferior wood. The latch devices comprise spring pins 24 projecting at the edge of the leaf in position to engage in the holes in brackets or keepers 25 fastened to the semi-circular frame 8, said brackets projecting upwardly beside the edge of the table top. The pins are connected by rods 26 to a bell crank lever 27 which is pivoted at 28 and the end 29 of which projects through an opening 30 in the edge of the leaf. When the leaves are pushed together as shown in Fig. 1 this projecting end 29 on one leaf enters a recess 31 in the meeting edge of the other leaf. When the lever 29 is turned by pushing in the projection 29, the pins 24 are drawn in and disengaged from the brackets 25, so that the leaf is then free to be swung up and turned around.

In operation, to reverse the leaves, the top is pulled apart slightly, as indicated in Fig. 2. The latches 24 are then disengaged as above described, and the leaf is swung up to vertical position. The lever 19 is then pulled out which shifts the wedge 17 to the left and lifts the leaf, as shown in Fig. 4. Then the leaf is turned on its pivot 11, as indicated in Fig. 2, half way around, and the leaf is then swung down to its original position, but with the opposite side uppermost, after which the wedge 17 is moved to the left to lower the leaf and cause the latches 24 to engage in the brackets 25. In this rotary action, the leaf is carried by the arm 13 and the pivot 11, the T-head 16 traveling around in the guide 15. The op-

posite leaf is then reversed in similar manner, and the top sections may then be pushed together. Or if an extension table be desired additional leaves can be put in place in the middle.

What I claim as new is:

1. In a table top, the combination of a supporting frame having a semi-circular guide, a central vertical pivot mounted in the frame, a leaf hinged to the top of said pivot, and a swinging supporting arm pivoted concentrically with said pivot and connected to the edge of the leaf, said arm having a projecting part which slides in said guide when the leaf is turned on the pivot.

2. In a table top, the combination of a supporting frame a central vertical pivot pin thereon, a leaf hinged to the top of said pin, and means engaging under the pin to lift the same and raise the leaf, said means comprising a wedge slidable on the frame and on which the pin rests.

3. In a table top, the combination of a supporting frame, formed in two extensible sections, a vertical pivot mounted on each section, a pair of leaves each of which is hinged at its meeting edge to each pivot, so that it may be turned with the pivot and also reversed with respect thereto, and means to lift each leaf, to clear the other leaf as it is being turned.

In testimony whereof, I affix my signature in presence of two witnesses.

LOUIS E. BINSFELD.
